PUMP

Walter W. Taylor, Oakland, Calif., assignor to
 Malsbary Manufacturing Company, Oakland,
 Calif., a co-partnership

Application July 3, 1945, Serial No. 603,069

9 Claims. (Cl. 103—9)

1

The present invention relates to improvements in pumps, and has particular reference to a double pump arrangement whereby two different liquids may be pumped to a common destination in separate paths.

My pump arrangement is particularly intended to be used in connection with a cleaning machine for motor vehicles, such as is disclosed in the Malsbary et al. Patent No. 2,295,228. In this patent it is proposed to provide a single pump for pumping from two tanks, one containing clear water and the other a concentrated cleaning solution, toward a heating coil for final discharge through a hose and a nozzle.

It was found subsequently that a diluted cleaning solution passing through a pump had certain injurious effects on the pump while a concentrated solution might pass through a pump without such effect.

It was proposed, therefore, in the co-pending application, Ser. No. 549,973, to provide two pumps, one for the clear water and one for the concentrated solution, both pumping toward the same coil.

It was further proposed, in the interest of economy and coordination, to interconnect the two pumps so that one would drive the other, through the medium of a fluid drive between the two pumps, whereby the reciprocating motion of the piston of the larger water pump would be transmitted to the reciprocating element of the smaller solution pump, which latter was presented as a diaphragm pump.

It was found, however, that a plain fluid drive between the two reciprocating members was unsatisfactory in certain respects on account of pressure losses, which would cause the diaphragm pump to develop less pressure than the main pump. This would make it impossible to force the diaphragm pump discharge into the main pump discharge, in the absence of compensating factors.

In the present invention it is proposed to provide a more positive drive between the reciprocating members of the pumps, comprising a combination of a rigid drive and a fluid drive whereby the advantages of the fluid drive are retained and the disadvantages are eliminated.

It is further proposed to introduce a compensating feature whereby excess pressures due to the rigid drive member are relieved and whereby the delivery of the auxiliary pump may be made subject to manual control.

Further objects and advantages of my invention will appear as the specification proceeds, and

the novel features of the same will be fully defined in the claims hereto attached.

The preferred form of the invention is illustrated in the accompanying drawing forming part of this application, in which:

Figure 1 shows a vertical section through my pump arrangement;

Figure 2, a horizontal section through the diaphragm pump, taken along line 2—2 of Figure 1; and

Figure 3, a face view of one of the castings used in my diaphragm pump, as seen from line 3—3 of Figure 1.

While I have shown only the preferred form of my invention, it should be understood that various changes or modifications may be made within the scope of the claims hereto attached without departing from the spirit of the invention. More particularly, I wish to point out that while I have shown the main pump as a piston pump and the auxiliary pump as a diaphragm pump, any suitable reciprocating pump may be substituted for either of them.

Referring to the drawing in detail, my pump arrangement comprises, in its principal features, a main pump 1 and an auxiliary pump 2. The main pump may be of any suitable form and is here shown as comprising a pump housing 3 having a piston 4 reciprocable therein and having a pump chamber 5, with suitable intake and discharge valves 6 and 7.

The pump is designed particularly for use in connection with a cleaning machine such as is described in the patent aforesaid and is intended for pumping clear water from a suitable supply, such as a watertank, to a heating coil for discharge through a nozzle. It is of the high pressure type and discharges at a pressure of 300 to 400 pounds.

The main pump is provided, opposite and in alignment with its piston, with a gland 8 having a restricted throat section 9, and a pipe 10, of larger diameter than the throat, is threaded into the gland, as shown at 11, the pipe being axially aligned with the piston.

The diaphragm pump comprises in its principal features a pair of similar annular castings 12—13 clamped upon the rim of a diaphragm 14 by means of bolts 15, the castings having concave portions 16 and 17 opposite the diaphragm to form chambers 18 and 19.

The casting 12 has a vertical passage 20 which is plugged at the ends, as at 21, and which communicates, through a series of central perforations 22, with the chamber 18. The passage also

communicates with chamber 18 at the highest and lowest points of the latter, through inclined ports 23-24, allowing air and dirt to escape from the chamber.

The diaphragm pump is connected to the main pump by being threaded on the pipe 10, as at 25, the pipe thus directly connecting with the passage 20, and through perforations 22, 23 and 24, with the chamber 18.

The casting 13 is shaped similarly to casting 12, and has a vertical passage 26 communicating with the chamber 19 through perforations 27 grouped about the centerline of the pump and ports 28-29, inclined to allow air to escape through the upper ports and dirt through the lower ones.

One end of the passage 26 may be plugged, as at 30, while the other end is preferably used to connect with the discharge valve 31. A suitable intake valve 32 may be provided on the outer face of the second casting.

The discharge valve delivers into pipe 33, which is preferably provided with a metering valve 34.

The piston 4 has a plunger 35 secured upon the end thereof and the plunger projects through the pump chamber 5 and the throat 9 of the gland 8 into the pipe 10, which latter may be considered as forming part of the diaphragm pump chamber 18.

The throat 9 is of a diameter slightly in excess of that of the plunger, so as to leave a slight clearance or leakage about the plunger, the clearance being preferably about five-thousandths of an inch.

The piston 4 is reciprocated, by any suitable means, through the connecting rod 36.

The intake 32 of the diaphragm pump, in the cleaning machine referred to, is connected to a solution tank, and the discharge 31 connects into the main pump discharge.

In operation, as the piston 4 is reciprocated, it draws in a charge of water through intake valve 6 on the suction stroke, and discharges water through valve 7 on the drive stroke. Disregarding the plunger 35, the piston would also draw on the diaphragm 14 on the suction stroke, creating a vacuum in chamber 19 and drawing in a charge of solution through the intake valve 32. On the drive stroke, the piston, disregarding the plunger, would create pressure on the diaphragm and force the latter into chamber 19 for discharging the liquid therefrom through valve 31.

Thus, even in the absence of the plunger 35, the piston 4 would cause the diaphragm to reciprocate with the piston, but the movement of the diaphragm would be relatively feeble, since on the suction stroke of the piston valve 6 opens, and on the drive stroke valve 7 opens to relieve the vacuum and the pressure.

Thus the diaphragm pump, in the absence of compensating features, would discharge at a pressure lower than that of the main pump and would be unable to force its discharge into the main pump discharge.

The plunger 35 is designed to produce a more positive drive for the diaphragm. It substantially separates chamber 18 of the diaphragm pump from chamber 5 of the main pump, and if the fit of the throat 9 about the plunger were leak proof, the action on the diaphragm would be substantially as positive as the action of the piston on the liquid in the main pump chamber.

But, this action would be too severe, in the absence of any cushioning means or relief outlet.

On the suction stroke, the suction would not only

pull the diaphragm into contact with the concave face of the casting 12, but would tend to draw the diaphragm material into the apertures 22; and on the drive stroke, the pressure would rise exceedingly high and would tend to squirt the water past the rim of the diaphragm to the outside of the pump.

The small clearance or leakage about the plunger remedies this defect, because it allows the pressures to equalize on opposite sides of the throat 9 while still maintaining substantially the same pressures in both pump chambers 5 and 19.

On the suction stroke, if an empty space should develop in the passage 20, which would tend to suck the diaphragm material into the perforations, enough water will leak past the throat 9 to fill the space. In view of the low pressure differential on the suction stroke, the water will not begin to leak through until the diaphragm has reached the limit of its travel.

On the pressure stroke the piston 4 drives the plunger 35 into the water and drives the diaphragm against the concave face of casting 13 to exhaust the charge from chamber 19. If any excessive pressure develops when the diaphragm reaches the limit of its stroke, water will leak back past the throat 9 into pump chamber 5, thus relieving the pressure in the diaphragm pump. It will be observed that the pressure in the diaphragm pump will still be the same as that in the main pump, since only excess pressure is relieved.

The leak at the throat 9 further adapts the diaphragm pump for control of its output by means of the metering valve 34. As the latter valve is closed down to reduce the output, the travel of the diaphragm becomes more limited and more water is made to leak past the plunger. The leak automatically limits the building up of pressure in the diaphragm beyond that of the main pump.

If the metering valve is closed altogether, all the water will leak past the throat in both directions and the diaphragm will remain unaffected by the movements of the plunger.

It is apparent that the leakage may be obtained by other means than those shown, as by small openings in the plunger or in the gland.

I claim:

1. In combination, a pump having a chamber and a piston reciprocable for pumping a liquid through the chamber, a second pump having a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and projecting into the pipe for operating the diaphragm through the liquid.

2. In combination, a pump having a chamber and a piston reciprocable for pumping a liquid through the chamber, a second pump having a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and projecting into the pipe for operating the diaphragm through the liquid, the pipe and the plunger being constructed to provide a slight leakage between the same for filling excess space in the second diaphragm chamber on the suction stroke.

3. In combination, a pump having a chamber and a piston reciprocable for pumping a liquid through the chamber, a second pump having a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and projecting into the pipe for operating the diaphragm through the liquid, the pipe and the plunger being constructed to provide a slight leakage between the same for discharging excess liquid in the second diaphragm chamber on the pressure stroke into the first pump chamber.

4. In combination, a pump having a chamber and a piston reciprocable for pumping a liquid through the chamber, a second pump having a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and projecting into the pipe for operating the diaphragm through the liquid, the pipe and the plunger being constructed to provide a slight leakage between the same for equalizing pressures on opposite sides of the leakage.

5. In combination, a pump having a chamber and a piston reciprocable for pumping a liquid through the chamber, a second pump having a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and projecting into the pipe for operating the diaphragm through the liquid, the pipe and the plunger being constructed to provide a slight leakage between the same, and a metering valve for controlling the output of the second chamber, the leakage causing an equalizing of pressure on opposite sides thereof for any adjustment of the metering valve.

6. In combination, a pump having a chamber and a piston reciprocable therein for pumping a liquid through the chamber, a second pump hav-

ing a diaphragm and chambers on opposite sides thereof, the diaphragm being adapted for pumping a liquid through one of the chambers, a pipe connection between the first pump chamber and the second diaphragm chamber for admitting liquid into the latter, and a plunger fixed to the piston and operable in the pipe with a slight leakage for operating the diaphragm through the liquid and for equalizing pressures on opposite sides of the leakage.

7. In combination, a pump having a chamber and a member reciprocable therein for pumping a liquid through the chamber, a second pump having a reciprocable member and chambers on opposite sides thereof, the latter member being adapted for pumping a liquid through one of the chambers, a restricted connection between the first pump chamber and the second chamber of the second pump for admitting liquid into the latter, and a plunger fixed to the piston and operable in the connection for operating the second member through the liquid.

8. In combination, a pump having a chamber and a member reciprocable therein for pumping a liquid through the chamber, a second pump having a reciprocable member and chambers on opposite sides thereof, the latter member being adapted for pumping a liquid through one of the chambers, a restricted connection between the first pump chamber and the second chamber of the second pump for admitting liquid into the latter, and a plunger fixed to the piston and operable in the connection for operating the second member through the liquid, the plunger being operable in the connection with a slight leakage for equalizing pressures on opposite sides of the leakage.

9. In combination, a pump having a chamber and a piston reciprocable therein for pumping a liquid through the chamber, a second pump having a pump chamber and a diaphragm subject to liquid pressures in the first chamber for pumping a liquid through the second chamber, a metering valve for controlling the output of the second pump chamber, and means for substantially equalizing the pressures in the two chambers at different settings of the metering valve.
